(57) CLAIM

I claim the ornamental design for the double-ended container, as shown and described.

DESCRIPTION

FIG. 1 is a three-dimensional perspective view of the double-ended container;

FIG. 2 is a front view of the double-ended container;

FIG. 3 is a bottom view of the double-ended container, the top view being a mirror image thereof; and,

FIG. 4 is a cross-section view along line 4—4 in FIG. 3 of the double-ended container.
